JAMES R. MCWANE, OF BIRMINGHAM, ALABAMA.

MEANS FOR POURING METAL IN THE FORMATION OF CAST-IRON PIPE.

1,386,268.

Specification of Letters Patent.

Patented Aug. 2, 1921.

Application filed March 23, 1920. Serial No. 368,170.

To all whom it may concern:

Be it known that I, JAMES R. MCWANE, a citizen of the United States, residing at Birmingham, in the county of Jefferson and 5 State of Alabama, have invented a new and useful Means for Pouring Metal in the Formation of Cast-Iron Pipe, of which the following is a specification.

This invention has reference to machines 10 for the centrifugal casting of iron pipe and the like, and its object is to provide a machine or apparatus whereby sensibly uniform casting may be obtained.

In accordance with the invention, the machine includes head and tail stocks capable 15 of receiving, supporting and rotating a suitable mold into which molten material, which may be specifically considered as molten iron, is received, and the mold with 20 the contained iron rotated, to cause the molten iron to flow to the inner walls of the mold and be there held by centrifugal force until the iron has chilled sufficiently in conformity with the mold to hold its shape.

25 It has been heretofore proposed to produce castings centrifugally and to produce iron pipe by centrifugal casting, but the difficulties presented have been such as to prevent any but short lengths of pipe from being produced.

30 In accordance with American and English practice, iron pipe is made in standard lengths of twelve feet to sixteen feet, but heretofore the difficulties encountered have 35 precluded the successful formation of such pipes by centrifugal casting, although the idea, if it could be successfully put into practice, would be highly advantageous.

35 This invention contemplates the employment 40 of structures whereby pipe of the standard lengths mentioned may be successfully formed by centrifugal casting without producing such weaknesses or other defects as would preclude the use of such centrifugal casting.

45 The invention will be best understood from a consideration of the following detailed description taken in connection with the accompanying drawings forming part 50 of this specification, with the understanding, however, that the invention is not confined to any strict conformity with the showing in the drawings, but may be changed and modified so long as such 55 changes and modifications mark no material departure from the salient features of

the invention as expressed in the appended claims.

In the drawings,

Figure 1 is an elevation of a centrifugal 60 casting apparatus with means for pouring the metal in accordance with the invention.

Fig. 2 is a plan view of the structure shown in Fig. 1, omitting some parts.

Fig. 3 is a detail of a stop used in connection with the ladle.

Referring to the drawings, there is shown a support or bed 1 of any suitable construction, with which uprights 2, 3 are associated at respectively opposite ends. The upright 2 carries at its upper end a rockable ladle 4 and the upright 3 similarly carries a rockable ladle 5. The ladle 4 is provided with trunnions 6 supported in journal bearings on the upright 2 and the ladle 5 is provided 75 with trunnions 7 carried by journal bearings on the upper end of the upright 3.

80 Mounted on the bed or support 1 at the end with which the upright 2 is associated is a head stock 8, and at the end associated with the upright 3 is a tail stock 9. The head and tail stock structures may be similar to and have functions like those of lathe head and tail stocks, the purpose being to receive and support a pipe mold 10, in 85 which the casting of the pipe is to be performed. Since the pipe to be made in the mold is of considerable length, which length as has hereinbefore been stated is twelve feet to sixteen feet standard, the apparatus 90 is correspondingly large. In an installation for the production of pipe on a commercial scale, track rails 11 are provided for the support of the molds in approaching the casting machines and in moving away therefrom, such arrangement facilitating the 95 handling of the molds.

100 The head stock 8 may be considered as adjustable along the support 1 by suitable means and the tail stock may also be adjustable along the support 1, but as such adjustability does not enter into the present invention, it need not be particularly shown and described. Adjacent to the head stock is a carriage 12 and adjacent to the tail 105 stock is a carriage 13. The carriage 12 is movable lengthwise of the bed 1 by the hand-wheel 14 and a rack 15. The carriage 13 is moved lengthwise of the bed 1 by a hand-wheel 16 and a rack 17.

110 A pulley 18 on the tail stock may be taken as representative of any suitable means for

the rotation of the mold 10. The carriage 12 carries a pouring gate 19 and the carriage 13 carries a pouring gate 20 permitting the introduction of molten metal into 5 the mold when the mold is secured in position on the casting machine.

Fast to one of the trunnions 6 is a sheave or pulley 21, and fast to one of the trunnions 7 is another sheave or pulley 22. The 10 sheave 21, together with the ladle 4, may be rotated by a handle 23 so as to tip the ladle from a normally upright position to a pouring position, permitting the ladle 4 to be completely emptied. Fast to the edge portion 15 of the sheave 21 is one end of a cable 24 carried over direction-changing pulleys 25 to the other sheave 22, to which the other end of the cable is made fast. The cable 24, when installed, has a certain amount of slack 20 so that the ladle 4 may be rocked for a distance before the slack is taken up, after which the ladle 5 will participate in the movement of the ladle 4. Furthermore, the sheave 22 is smaller than the sheave 21, say 25 about half the diameter, so that the full rocking movement of the ladle 5, in pouring, may take place after the ladle 4 has poured about half its charge, and the ladle 5 may be emptied while the ladle 4 still contains a 30 small portion of its charge, the remnant of the charge of the ladle 4 representing about the amount of metal which it takes to fill the bell end of the pipe mold beyond the diameter of the body of the pipe.

35 In the installed apparatus, molten metal is carried to the ladles 4 and 5 by a much larger ladle 26, which latter may be carried by a suitable crane (not shown in the drawings).

40 It has heretofore been found to be practically impossible to cast pipe by the centrifugal process if the pipe was longer than a small fractional portion of the length of standard cast iron pipe; that is, when the 45 pipe is as much as twelve feet or sixteen feet in length. This has been found to be due to the introduction of the molten metal into one end of the mold because the metal, in flowing toward the other end of the mold, 50 becomes more or less cooled and therefore dull and sluggish. Moreover the metal has a tendency to flow toward the farther end and rebound in the form of a wave which is noticeable in the metal, even after the mold 55 has been rotated and the metal is driven outwardly by centrifugal force and finally set. The result of this is a pipe of varying thickness of wall and corresponding variation in strength, which can only be overcome by excessive speed of revolution. Furthermore, the wave formation tends to carry the loose sand of the mold and impurities in the iron into a circumscribed area where such impurities become fixed on cooling and 60 the pipe is correspondingly weakened.

Surging of the molten metal, due to pouring the charge into one end of the mold, is minimized by this invention by pouring the charge into both ends of the mold but not simultaneously. The charge from the ladle 70 4 is started into the bell end of the mold until about half the contents of the ladle 4 is discharged. By this time the slack of the cable 24 is taken up and continued tilting of the ladle 4 causes a tilting of the ladle 5 75 in a direction to pour its contents into the funnel 20. As the tilting of the ladle 4 progresses, the ladle 5 tilts but with considerably greater rapidity so that by the time the ladle 4 approaches but has not yet 80 reached the fully discharged position the ladle 5 has completed the discharge of its contents.

The molten metal initially poured from the ladle 4 enters the mold 10 at the bell end 85 thereof, this being the end corresponding to the bell end of the completed pipe, and the molten metal flows toward the opposite end of the mold considerably beyond the middle thereof. During this movement of the 90 molten metal, more or less debris is carried along at the head of the flow and the forward end of the flow becomes more or less dull and sluggish. As soon, however, as the flow from the second ladle begins, the second 95 batch of metal progresses along the pipe mold toward the bell end of the mold and meets and livens up the first flow of molten iron so that when the pouring is completed the tendency to surging is counteracted and 100 the iron in the mold is of very nearly uniform temperature throughout. If the iron from the two ladles were poured in simultaneously at both ends of the mold, the dull iron would go to the center from each ladle, 105 causing at this point an excess of sluggish metal and impurities and therefore resulting in weakness.

When the mold begins to revolve, the 110 tendency of the molten metal is to flow away from the axis of rotation and this tendency is more pronounced as the distance from the axis of rotation increases. The result of this is that the mass of metal in the mold immediately adjacent to the 115 bell end is robbed to fill the bell end to an extent causing a thinning of the walls of the forming pipe. Therefore, after the revolving of the mold to cause centrifugal action has been commenced, the remainder of the metal in the ladle 4 is poured into the mold, thus supplying a sufficient quantity of molten metal to make up for the amount removed centrifugally from the immediate neighborhood of the bell end of the pipe.

In order to automatically determine the amount of metal to be retained in the ladle 4, there is provided a stop 27 mounted to rock on the bar 28 carried by the upright 2 in the path of the ladle 4. The arm 27 is 120 125 130

provided with a counterweight 29 tending to urge it toward the ladle 4 so that when the latter is rocked to pour metal therefrom the stop 27 is engaged with the ladle and caused 5 to move with it. However, the arm 27 or counterweight 29 has normally in its path a stop pin 30, which pin is carried by the upright 2 in such manner as to be readily removed therefrom, thus allowing the stop 10 27 to move farther in the direction of pouring movement of the ladle 4. This additional movement of the ladle results in the discharge of the metal retained in the ladle, but as the ladle 5 is at this time already emp- 15 tied, further tilting has no effect upon it.

While the pouring of the metal into the mold may be performed by two operatives each stationed at a respective ladle, the attempt to maintain a certain timed relation 20 between the pouring movements, by one operative being guided by the other, is uncertain in results. With the structure of this invention, a single operative controlling the handle 23 is able to cause the pouring to 25 occur in predetermined order with certainty of results and with greater rapidity than could be done where the manipulation of the two ladles depended upon unrestricted movement of independent operatives.

30 What is claimed is:—

1. In the casting of iron pipe and the like centrifugally in rotatable molds having pouring gates at opposite ends, connected mechanical means for introducing molten 35 metal into the mold through both gates simultaneously.

2. In the casting of iron pipe or the like centrifugally in rotatable molds having pouring gates at opposite ends, means for 40 introducing molten metal into the mold through one gate, and means for then introducing molten metal into the mold through both gates simultaneously, said means at the opposite ends of the mold being timed to 45 complete the introduction of the molten metal at the second named end of the mold prior to the completion of the introduction of the molten metal at the first named end of the mold.

50 3. In the casting of iron pipe and the like centrifugally in rotatable molds having pouring gates at opposite ends, means for introducing a predetermined amount of molten metal into one end of the mold, 55 means for then introducing a predetermined amount of molten metal into the other end of the mold, and means for introducing additional molten metal into the first named end of the mold until the full amount of 60 molten metal desired has been deposited in both ends of the mold.

4. In the casting of iron pipe and the like centrifugally in rotatable molds having pouring gates at opposite ends, means for 65 introducing a determined amount of molten

metal into one end of the mold through the pouring gate thereat, means timed with relation to the first named means for then pouring molten metal into the other end of the mold through the pouring gate thereat 70 with the pouring continuing at both ends of the mold until the full determined amount has been deposited in the second named end of the mold, and means whereby the pouring is continued into the first named end of the mold subsequent to the completion of the pouring at the second named end of the mold until the mold has received its full charge.

5. In the casting of iron pipe and the like 80 centrifugally, means for pouring molten metal into rotatable molds having pouring gates at opposite ends, comprising a ladle at each end of the mold tiltable to deposit the molten metal into respective gates, and connections between the tiltable ladles provided with lost motion parts whereby the tilting of one ladle will cause the tilting of the other ladle after the tilting of the first ladle has progressed for a predetermined time.

6. In the casting of iron pipe and the like centrifugally, means for pouring molten metal into rotatable molds having pouring gates at opposite ends, comprising tiltable 85 ladles in operative relation each to a respective gate, and lost motion connections between the ladles having a predetermined amount of slack whereby the tilting of one ladle causes the tilting of the second ladle after the tilting of the first ladle has progressed to a predetermined extent.

7. In the casting of iron pipe and the like centrifugally, means for pouring molten metal into rotatable molds having pouring gates at opposite ends, comprising tiltable 105 ladles for molten metal each associated with a respective gate, and slack flexible connections between the ladles for causing the rocking of one ladle to produce a rocking movement in the other ladle, the slack being 110 enough to permit one ladle to rock sufficiently to pour about half its contents into the adjacent gate before the second ladle is moved to pouring position.

8. In the casting of iron pipe and the like 115 centrifugally, means for pouring molten metal into rotatable molds having pouring gates at opposite ends, comprising tiltable 120 ladles for molten metal each associated with a respective gate, and slack flexible connections between the ladles for causing the rocking of one ladle to produce a rocking movement in the other ladle, the slack being 125 enough to permit one ladle to rock sufficiently to pour about half its contents into the adjacent gate before the second ladle is moved to pouring position, and the second ladle having means to which the connections are attached and proportioned to cause the 130 rocking of the second ladle to the fully

oured position before the first ladle reaches the fully poured position.

9. In the casting of iron pipe and the like centrifugally, means for pouring molten metal into rotatable molds having pouring gates at opposite ends, comprising rockable ladles at respective ends of the mold, means whereby one ladle may be tipped toward the pouring position, means for causing the second ladle to tip toward the pouring position after the first has partly completed its pouring, with both ladles then continuing the pouring movement until the second ladle is empty and the first ladle has completed the greater portion of its pouring movement, and means for permitting the completion of the pouring movement of the first ladle after the second ladle has become empty.

10. In the casting of iron pipe and the like centrifugally, means for pouring molten metal into rotatable molds having pouring gates at opposite ends, comprising two rockable ladles at respectively opposite ends of the mold, means for tipping first one and then the other ladle toward pouring position in predetermined order, with the movement of the ladles then simultaneous for a portion of their travel until the second ladle is empty, means for stopping the movement of the first ladle near the completion of its pouring movement to hold back a portion of its charge, and means whereby the first ladle may be released to complete its pouring movement.

11. In the casting of iron pipe and the like centrifugally, means for pouring molten metal into rotatable molds having pouring gates at opposite ends, comprising rockable ladles individual to the respective gates and of a combined capacity sufficient for the mold, and connections between the ladles for causing them to move in succession for a portion of their pouring travel and then simultaneously, with the second ladle completing its pouring before the first ladle.

12. In the casting of iron pipe and the like centrifugally, means for pouring molten metal into rotatable molds having pouring

gates at opposite ends, comprising rockable ladles individual to the respective gates and of a combined capacity sufficient for the mold, and connections between the ladles for causing them to move in succession for a portion of their pouring travel and then simultaneously, with the second ladle, completing its pouring before the first ladle, and the first ladle having means whereby a part of its contents may be withheld and subsequently poured into the mold to complete the pouring operation.

13. In the casting of iron pipe and the like centrifugally, means for pouring molten metal into rotatable molds having pouring gates at opposite ends, comprising rockable ladles individual and adjacent to the gates, with the ladles of a combined capacity corresponding to that of the mold, sheaves on the respective ladles with one sheave of greater diameter than the other, and a cable connecting the sheaves and having a normal slack whereby on rotating the larger sheave the smaller sheave will be actuated after the slack in the cable is taken up and the first ladle has been rocked for a predetermined distance.

14. In the casting of iron pipe and the like centrifugally, means for pouring molten metal into rotatable molds having pouring gates at opposite ends, comprising rockable ladles individual and adjacent to the gates, with the ladles of a combined capacity corresponding to that of the mold, sheaves on the respective ladles with one sheave of greater diameter than the other, and a cable connecting the sheaves and having a normal slack whereby on rotating the larger sheave the smaller sheave will be actuated after the slack in the cable is taken up and the first ladle has been rocked for a predetermined distance, the sheaves being proportioned to cause a more rapid movement of the second ladle than of the first ladle.

In testimony that I claim the foregoing as my own, I have hereto affixed my signature.

JAMES R. McWANE.
